US0D1020130S

(12) **United States Design Patent** (10) **Patent No.:** **US D1,020,130 S**
(45) **Date of Patent:** **** Mar. 26, 2024**

(54) **ANIMAL TAG**

(71) Applicant: **HerdDogg, Inc.**, Laramie, WY (US)

(72) Inventor: **Melissa Brandao**, Laramie, WY (US)

(73) Assignee: **HerdDogg, Inc.**, Laramie, WY (US)

(**) Term: **15 Years**

(21) Appl. No.: **29/788,437**

(22) Filed: **May 26, 2021**

(51) **LOC (14) Cl.** **30-08**

(52) **U.S. Cl.**

USPC **D30/155**

(58) **Field of Classification Search**

USPC D30/155, 199; D10/106.9, 106.91,
D10/106.92; D20/22, 23, 24, 27, 28

CPC A01K 11/00; A01K 11/001; A01K 11/004;
A01K 11/006; A01K 11/008

(57) **CLAIM**

The ornamental design for an animal tag, as shown and described.

DESCRIPTION

FIG. 1 is an isometric view of the design.

FIG. 2 is a front view of the design of FIG. 1.

FIG. 3 is a rear view of the design of FIG. 1.

FIG. 4 is a right side view of the design of FIG. 1.

FIG. 5 is a left side view of the design of FIG. 1.

FIG. 6 is a top plan view of the design of FIG. 1; and,

FIG. 7 is a bottom plan view of the design of FIG. 1.

The long-dashed broken lines in FIG. 1 illustrate environmental structure that forms no part of the claimed design, and the short-dashed broken lines in FIGS. 1, and 7 illustrate portions of the article that form no part of the claimed design.

1 Claim, 4 Drawing Sheets
